DESIGN FOR A SWEATER

Joseph Engelberg, New York, N. Y.

Application April 21, 1936, Serial No. 62,231

Term of patent 3½ years

To all whom it may concern:

Be it known that I, Joseph Engelberg, a citizen of the United States of America, residing in Manhattan, county of New York, and State of New York, have invented a new, original, and ornamental Design for a Sweater, of which the following is a specification, reference being had to the accompanying drawing, forming part thereof, wherein.

The lines radiating from the lower extremity of the collar portion represent fringe.

I claim:

The ornamental design for a sweater, substantially as shown, and described.

JOSEPH ENGELBERG.
